UNITED STATES PATENT OFFICE

154,233

DESIGN FOR A RING

Arthur David Bastien, Williamstown, Mass.

Application July 22, 1948, Serial No. 147,712

Term of patent 7 years

(Cl. D45—10)

To all whom it may concern:

Be it known that I, Arthur David Bastien, a citizen of the United States of America, residing at Williamstown, in the county of Berkshire and State of Massachusetts, have invented a new, original, and ornamental Design for a Ring, of which the following is a specification, reference being had to the accompanying drawing, forming a part thereof.

In the drawing:

Figure 1 is a plan view of a ring embodying my new design;

Figure 2 is a side elevational view of the same;

Figure 3 is a side elevational view of the same showing the side opposite from Figure 2.

I claim:

The ornamental design for a ring, as shown
ARTHUR DAVID BASTIEN.
